HIGH-FREQUENCY VARIABLE INDUCTANCE

Jack L. Bowers, Dayton, Ohio, assignor to the
United States of America as represented by the
Secretary of War

Application December 6, 1944, Serial No. 566,935

6 Claims. (Cl. 171—242)

(Granted under the act of March 3, 1883, as
amended April 30, 1928; 370 O. G. 757)

1

The invention described herein may be manufactured and used by or for the Government for governmental purposes, without the payment to me of any royalty thereon.

The invention to be hereinafter described relates to a variable inductance adapted to be used as a tuning element in a high frequency radio circuit.

Heretofore difficulty has been experienced in removing (electrically) the unused portion of an inductance, due to the character of very high frequency currents.

Furthermore, it has been common practice to tune the capacitor rather than the inductance because of the above difficulty.

The only common method of tuning inductance uses a single roller contacting only a single helix at a single point as it travels the coil. That method does nothing to remove the electrical effect of the by-passed helices.

The main objects of the present invention are to completely eliminate or greatly minimize the above and other objections and provide a simple and efficient variable inductance in which the by-passed helices of the coil will definitely, reliably and permanently be removed as far as electrical effect is concerned.

In order to more clearly disclose the construction, operation and use of the invention, reference should be had to the accompanying drawings forming part of the present application.

Throughout the several figures of the drawings like reference characters designate the same parts in the different views.

In the drawings:

Figure 1 is a front view of the invention;

Figure 2 is a top plan view;

Figure 3 is an enlarged end view of one coil assembly in operative position, showing connection of slug to coil; and

Figure 4 is an enlarged fragmentary cross section through one of the connections shown in Figure 3.

Referring to the drawings in detail, the variable inductance comprises a coil A, two being shown in the particular arrangement illustrated, suitably mounted on ceramic or other insulating blocks or supports B and reciprocably receiving cylindrical slugs C of suitable conducting material.

In order to definitely and reliably short out or remove, electrically speaking, the unused portion of an inductance, usually helices of a coil, the movable member such as the slug C in this case, must remain either in actual contact with the coil member or so close thereto as to cause no more than negligible impedance to high frequency currents.

In the present invention the coils are shown as cylindrical. The slugs C are of substantially

2

the same lengths as the coil, preferably somewhat longer. They are slightly less in outside diameter than the inside diameter of their respective coils. This difference should be sufficient to enable the slug to both rotate within and travel freely longitudinally through its respective coil, without actual contact with said coil. That permits movement of the slug within and through the coil without friction due to contact. At the same time, it maintains the radial distance between the coil and slug at a point where the impedance to high frequency currents will be only negligible. It also assures a continuous slug surface in close proximity to the coil throughout the length of that portion of the slug within the coil.

In the present instance the invention is shown as coupled with a magnetron type oscillator of known construction. In such relation it is used as the inductive portion of a tuned circuit, in which the capacitance is derived from the distributed capacitance of the magnetron tube and the inductance itself. To obtain lower operating frequencies additional fixed capacitance may be added in parallel with the inductances, in well known manner.

In the present preferred arrangement, a shaft 1 extends axially through the aligned coils A and the slugs C are slidably and revolvably mounted on that shaft, either directly on it or indirectly on it. Each slug is connected by a pair of rods 2 with a toothed disc, plate or large gear 3 mounted on shaft 1. One gear 3 is driven through a suitable gear train, by hand or by any other suitable and acceptable means. The other gear will be driven by a counter shaft 4 and intermeshed smaller gears 5. In the present instance, the gear drive is so proportioned as to travel the two slugs C at the same rate.

The longitudinal travel of each slug is effected in the same way and by the same devices. A description of one set of such devices will, accordingly, cover both. A preferred arrangement is to provide the inner, forward or lead end of the slug with radially extending small yokes 6 having approximately semi-circular concave seats or sockets which, in operative position, fit about, embrace and receive the conductor rod, wire or tube of coil A. Yokes 6 are slidably mounted in blocks 6' extending radially from the respective slug and provided with radial socket 7 for freely slidably receiving yoke 6. A yieldingly compressible device such as a coil spring 8 confined in socket 7 between yoke 6 and block 6' continuously maintains sliding contact between coil A and yoke 6. As shown, and as preferred, three such yokes are used at the respective end of each slug and those of each slug are equally spaced circumferentially, providing a substantially continuous contact, electrically, throughout the respective helix. With both slugs thus slid-

ably connected to their respective coils, rotation of the slugs by the above gear drive compels corresponding axial or longitudinal travel of them relative to their respective coils with corresponding variation of inductance. Reverse drive effects reverse travel. This construction and operation make possible regular, continuous, progressive and uniform travel or feed of the slug. Preferably a wiping contact 9 is provided on one of the yoke blocks 6' associated with each slug C, this electrical contact 9 slidingly engaging shaft 1. Due to the forward position of each contact 9 with respect to its slug C this reduces the electrical path between the slug contacts of the respective coils. This permits operation at higher frequencies than would otherwise be possible with the same equipment. While two coils and slugs have been shown, it will be well understood that one only or more than two may be used and are equally within the invention.

Likewise, three equally spaced connections between slug and coil have been stated as preferred. Any number of such connections from one up may be used but three equally spaced have been found highly satisfactory. Also, grooved rollers instead of yokes 6 have been found very practical. Many other connections may be used provided they cause the slugs to follow the spiral of the coil in substantially the same way. For instance, the slugs could be formed with spirally disposed ribs to fit between the helices of the coils so that when rotated the slugs would have the same action and movement as a screw being turned into its bore or socket. That, however, is undesirable because of the high degree of friction it would involve. Likewise, in cases where more than one coil and slug are used, the slugs need not be operated at the same rates but may be operated at different rates as may best suit the respective circumstances.

Although the coil and slug have been referred to and shown as a slug within a coil, it hardly need be stated that the relation, in that respect, may be reversed: i. e., the slug element may be outside and the coil inside, and there may be a considerable variation in that relative assembly also. In all cases, the close relative, radial positions of the parts must be maintained, however, to avoid more than negligible impedance to high frequency currents.

It is thought that the construction, operation and use of the invention will be clear from the preceding detailed description.

Changes may be made in the construction, arrangement and disposition of various features of the invention, within the scope of the appended claims without departing from the field of the invention and it is meant to include all such within this application, wherein only one preferred form has been illustrated purely by way of example and with no thought or intent of, in any degree, limiting the invention thereby.

Having thus described my invention, what I claim and desire to protect by Letters Patent is:

1. A variable inductance for high frequency radio circuits comprising a coil, means for supporting said coil in a fixed position, an electrically conductive slug element movable longitudinally relatively to said coil, means for moving said slug element, a plurality of blocks carried by and extending radially from said slug and provided with yoke receiving sockets, coil engaging and following yokes reciprocable in said sockets and means within said sockets engaging said yokes

and yieldingly maintaining the same in operative engagement with the aforesaid coil.

2. A variable inductance for high frequency radio circuits comprising a coil, means for supporting said coil in a fixed position, an electrically conductive slug element movable longitudinally relatively to said coil and having a diameter sufficiently large to render negligible the impedance to high frequency currents, means for moving said slug element, a plurality of blocks carried circumferentially equi-distantly distributed by said slug and extending radially therefrom said blocks being provided with yoke receiving sockets, a coil engaging and following yoke reciprocable in each said socket and means within each said socket engaging the respective yoke and yieldingly maintaining the same in operative engagement with the aforesaid coil.

3. A variable inductance for high frequency radio circuits comprising a plurality of coils, means for supporting said coils in fixed positions, an electrically conductive slug element movable longitudinally relatively to each of said coils and having a diameter sufficiently large to render negligible the impedance to high frequency currents, a plurality of blocks carried by and extending radially from each of said slugs and provided with a yoke receiving socket, coil engaging and following yokes reciprocable in said sockets, means within said sockets engaging said yokes and yieldingly maintaining the same in operative engagement with the aforesaid coil and means for moving said slug elements synchronously.

4. In combination, an inductance coil, an electrically conductive slug closely fitting adjacent the convolutions of said coil to render negligible the impedance thereof to high frequency currents, means associated with said slug forming an electro-mechanical connection to said coil, and means for longitudinally adjusting said slug relative to said coil.

5. A variable inductance comprising a coil, an electrically conductive slug element revolvably and longitudinally movable relative to said coil and closely fitting adjacent the convolutions of said coil to render negligible the impedance thereof to high frequency currents, and electrical contact means associated with said slug element slidably engaging said coil.

6. A variable inductance comprising in combination a pair of coils, an electrically conductive slug associated with each coil, each slug closely fitting adjacent the convolutions of its respective coil to render negligible the impedance thereof to high frequency currents, an electrically conductive shaft extending longitudinally of said coils and supporting said slugs for rotation, electrically conductive means associated with each said slug slidably engaging the corresponding coil, and an electrical contact fixed to each said means and slidably engaging said shaft.
